(57) **CLAIM**

The ornamental design for a curtain rod finial, as shown and described.

DESCRIPTION

FIG. 1 is a perspective view of the curtain rod finial showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines shown in the drawings are included for the purpose of illustrating portions of the curtain rod finial that form no part of the claimed design.
